UNITED STATES PATENT OFFICE

ERNEST E. CHARLTON, OF SCHENECTADY, NEW YORK, ASSIGNOR TO GENERAL ELECTRIC COMPANY, A CORPORATION OF NEW YORK

GASEOUS CONDUCTION DEVICE

Application filed July 17, 1924. Serial No. 726,640.

The present invention relates to electric discharge devices which operate by the ionization of a gas, and it is the object of my invention to improve the efficiency and reliability of these devices.

Gaseous conduction devices, such as glow discharge lamps and rectifiers, which are charged with an inert gas, such as neon or helium, operate by virtue of the ionization 10 of the gas when a sufficiently high voltage is impressed upon the electrodes.

In order to reduce to a minimum the voltage necessary to produce this discharge between the electrodes, it has been found 15 advantageous to introduce small amounts of alkali metals, such as sodium or potassium, into the bulb. These metals being highly oxidizable combine with deleterious gases which may be evolved from the walls of the 20 bulb during operation.

In a gas discharge rectifier for alternating current the presence of alkali metal at an appreciable vapor pressure is apt to increase 25 the likelihood of undesired reverse discharges in the rectifier and in a gaseous glow lamp the alkali metal tends to obscure the light emission by the formation of a film on parts of the bulb surface.

I have discovered that the voltage necessary 30 for operating devices of this class may be reduced without these disadvantages by providing in the bulb together with an inert gas, an oxide of an alkali metal, preferably associated with a highly oxidizable metal 35 such as an alkaline earth metal. Apparently, the alkali metal oxide combines with hydrogen which appears to be formed by the decomposition of water vapor and also with such gases as carbon monoxide which sometimes are evolved from the electrodes during 40 the operation of the device. The novel features of my invention will be pointed out with greater particularity in the appended claims.

45 The accompanying drawings show for

illustrative purposes two forms of discharge devices to which my invention is applicable. Fig. 1 shows partly in section an ionization rectifier for alternating current and Fig. 2 shows in perspective an ionization glow 50 lamp.

The rectifier shown in Fig. 1 comprises a bulb consisting as usual of glass and containing anodes 2, 3 which have a small exposed surface and are respectively surrounded by housings 4, 5. The latter are connected together and form a single cathode having relatively much larger surface than either of the anodes. Ordinarily, the surface of the cathode is more 55 than 300 times as great as the surface of either of the anodes. The anodes 2, 3 conveniently are constituted by the exposed ends of wires 6, 7 passing through the glass tubes 8, 9 which form an extension of 60 the glass stem 10. Although these wires may consist of any metal which is not readily vaporizable by electric discharges, I prefer to employ tungsten as it is readily sealed into a hard glass, such as a sodium-magnesium 65 boro-silicate. The cathode conveniently consists of nickel. The anode conductors 6, 7 together with the cathode conductors 11, 12 are sealed to the external contacts 13 of a bayonet type base 14.

In the manufacture of the device, the bulb 1 is first baked out at a temperature of about 450° C. to remove water vapor and is evacuated in the usual manner (the tubulation through the base not being shown). After 80 the evacuation a small amount of an alkali metal, preferably caesium, is introduced into the bulb 1 and this metal is oxidized by the admission of a small quantity of oxygen and warming of the bulb to somewhat above room temperature, say to about 50° C. The excess oxygen is pumped out. Instead of caesium other alkali metal may be used in the preparation of the device, but among these metals caesium and rubidium are preferred. Prefer- 85 90

ably a small quantity of alkaline earth metal, such as magnesium or calcium, is deposited on the bulb before the gas filling is admitted. This metal may be affixed to one of the electrodes, (conveniently the cathode as indicated at 15), prior to the assembly of the device. It can be vaporized by introducing the device into a high frequency electromagnetic field.

The bulb is finally charged with an inert gas, preferably helium or neon, at a pressure which may vary between the limit of about 5 to 80 millimeters of mercury. A pressure of about 19 millimeters of mercury is preferred. Other gases of the rare gas group 15 may be used but either helium, or a mixture of helium and neon is preferred. By the chemical affinity of the alkaline earth metal and the alkali metal oxide for such gases as hydrogen and carbon monoxide, the voltage 20 drop in the rectifier during operation is lowered about 30%. The large exposed surface obtained by the condensation of the alkaline earth metal and the oxide of the alkali metal on the inner surface of the bulb materially 25 enhances the reactivity of these metals for deleterious gas. As metals of the alkaline earth group have an inappreciable vapor pressure at the operating temperature of a gaseous glow device, the presence of this metal 30 will not cause undesired electric discharges. In some cases, instead of introducing the alkali metal and the alkaline earth metal separately, a mixture of a halide of an alkali metal, as, for example, caesium chloride together with an excess of alkaline earth metal 35 is applied upon the electrode or other convenient place. This mixture may be compressed into the form of a small pellet. When this mixture is heated, a reaction takes place 40 evolving the alkali metal in the elemental state. Continued heating, therefore, causes both the alkali metal and alkaline earth metal to be vaporized and to be deposited upon the inner surface of the bulb. 45 When oxygen is admitted and the bulb is warmed, the alkali metal is oxidized, but if care is taken not to raise the temperature much above 50° C. the alkaline earth metal is not appreciably oxidized. Some alkali 50 metal is likely unavoidably to remain un- oxidized. The uncombined oxygen then is removed and finally the inert gas is introduced as above described. Certain structural features in the rectifier shown in Fig. 1 whereby 55 discharges between the anodes are inhibited by the shielding effect of the cathode are claimed in my copending application, Serial No. 726,638 filed herewith.

My invention also may be applied with ad- 60 vantage to the production of gaseous glow lamps. In the glow lamp shown in Fig. 2 the electrodes 17, 18 are constituted of plates of iron, nickel, molybdenum, aluminum or other suitable material, which is not appreci- 65 ably vaporized at the operating temperature

of such a lamp. The electrodes are connected as usual to leading-in conductors 19, 20 which are sealed into a glass stem 21 and are joined by screws 22, 23 to the electrodes 17, 18. The electrodes are separated by a sheet 24 of refractory dielectric material, for example, fused quartz or hard glass. A small piece of insulation 25, for example mica, is provided to insulate the conductor 19 from the electrode 18, the screw 22 contacting with the electrode 17. The drawings also show supporting anchors 26, 27 for the electrodes but, of course, these structural features are shown for illustrative purposes only and have no particular bearing upon my invention.

In the glow lamp as well as in the rectifier, the bulb is first freed from water vapor by baking in the usual manner and it is then exhausted to a high vacuum. The alkali metal, either alone or together with the alkaline earth metal, may be introduced by either of the methods described in connection with Fig. 1. For example, a pellet consisting of a mixture of alkali metal halide and an excess of alkaline earth metal, for example, caesium, chloride and magnesium, may be placed within a heater 28 consisting of a spiral refractory filament, tungsten, for example, which is connected between the leading-in conductors 19, 20. Upon the application of heat the reaction occurs, above indicated, causing some of the alkali metal to be vaporized. The filament may be finally burned out by passing an excess current through the same. A quantity of oxygen then may be admitted by a tube 29, connections to the vacuum pump being closed by a cock 30. The alkali metal is oxidized at a temperature at which the alkaline earth metal is not appreciably oxidized. The excess oxygen is pumped out. Neon or other rare gas, or rare gas mixtures, then are admitted at a desired pressure varying usually between a few millimeters and a few centimeters of mercury, depending on conditions.

In a lamp, to insure transparency of the bulb, the caesium or other alkali metal may be introduced as a vapor from an external source, and then oxidized by the introduction of oxygen gas before introducing the neon, or other gas filling.

What I claim as new and desire to secure by Letters Patent of the United States, is,—

1. The method of preparing a gaseous glow device which consists in evacuating a bulb, introducing a small amount of alkali metal into said bulb, admitting a small amount of oxygen, heating the bulb to a temperature at which oxidation of alkali metal occurs, removing the uncombined oxygen, introducing an alkaline earth metal into said bulb and finally providing the bulb with a desired gaseous filling.

2. The method of preparing a gas filled glow discharge device which consists in evacuating a container provided with suitable

electrodes, introducing a small amount of alkali metal into said container, admitting sufficient oxygen to convert said alkali metal to an oxide, removing excess of oxygen and 5 introducing a rare gas at a pressure materially less than atmospheric pressure, together with a material which is capable of combining with undesired gases and has an inappreciable vapor pressure at the operating temperature of said device.

In witness whereof, I have hereunto set my hand this 16th day of July, 1924.

ERNEST E. CHARLTON.
